FRED. J. KALDENBERG.

UNITED STATES PATENT OFFICE.

FREDERICK J. KALDENBERG, OF NEW YORK, N. Y.

DESIGN FOR A THERMOMETER.

SPECIFICATION forming part of Design No. 13,470, dated December 5, 1882.

Application filed October 27, 1882. Term of patent 7 years.

To all whom it may concern:

Be it known that I, FREDERICK J. KALDENBERG, a citizen of the United States, residing at New York, in the county and State of New York, have invented and produced a new and original Design for Thermometers or Thermometer-Supports, of which the following is a specification.

The nature of my design is fully represented 10 in the accompanying photograph, to which reference is made, and which is a view in perspective of my newly-designed thermometer holder or stand.

My invention aims to provide a unique and 15 fanciful design for the supports or stands for holding thermometers and similar instruments; and the leading feature of such design consists of a tooth or tusk shaped column upheld by a negro.

20 In the illustration, *a* represents a base portion of the stand, which is flat in general contour, and upon which is erected the tusk or tooth *b* and figure *c*. On the front or face of the tusk or tooth *b* is mounted a thermometrical instrument, *d*. The tusk or tooth *b* is represented inclining backward, and as being upheld or braced up in position by the figure *c*, which in color and dress simulates an African negro in his natural condition, and whose uplifted hands and upturned face make him appear as if in the act of elevating the tusk-shaped column *b*.

The entire design, with the exception of the thermometer, may be made of similar material—such as ivory—and the tusk-shaped column *b* may be the natural tusk or tooth of an animal; but to produce a more marked and striking effect the tusk and base portion may be white or ivory color, and the figure *c* black, as here shown, so as to better illustrate the real aspect of the negro.

I claim as my invention—

1. The design for a stand for a thermometer or similar article herein shown and described, consisting of a tusk or tooth shaped column 45 supported by a human figure with uplifted hands, and mounted on a base portion.

2. The design for a support or stand for thermometers herein shown and described, the same consisting of an animal's tusk or tooth 50 represented as supported in an inclined position by a negro in characteristic dress and with uplifted head and hands.

3. The design for thermometer-holders, composed of a tusk, *b*, mounted on a base, *a*, and inclining backward, and supported at the rear by the figure *c* simulating an African negro, substantially as described and shown.

FRED. J. KALDENBERG.
